UNITED STATES PATENT OFFICE.

DENNIS H. TIERNEY, OF WATERBURY, CONNECTICUT.

CORSET-CLASP.

SPECIFICATION forming part of Letters Patent No. 257,106, dated April 25, 1882.

Application filed February 27, 1882. (No model.)

To all whom it may concern:

Be it known that I, DENNIS H. TIERNEY, of Waterbury, in the county of New Haven and State of Connecticut, have invented a new Improvement in Corset-Clasps; and I do hereby declare the following, when taken in connection with accompanying drawings and the letters of reference marked thereon, to be a full, clear, and exact description of the same, and which said drawings constitute part of this specification, and represent, in—

Figure 1, a front view; Fig. 2, a rear view, the parts in their locked position; Fig. 3, a rear view, the parts in the unlocked position; Fig. 4, a side view; Fig. 5, a transverse section; Figs. 6 and 7, modifications.

This invention relates to an improvement in devices for locking the clasps of a corset, so as to prevent the accidental detachment when on the person; and it consists in the construction hereinafter described, and particularly recited in the claims.

A represents one busk, spring, or steel, on which are the studs a; B, the other busk, steel, or spring, on which are the eyes b, in substantially the usual manner.

On the back of the busk to which the eyes are attached I arrange a narrow strip of metal, C, slotted as at d, and attached to the principal busk, B, by studs, through respective slots, so that the piece C is free for longitudinal movement on the busk B. From the piece C projections f extend toward the eyes, (see Figs. 2 and 3,) so that moving the piece C in one direction the projections f are brought over the enlarged part of the eye, as seen in Fig. 2, or in the opposite direction they are moved off from the said enlarged part of the eye.

The busks are clasped together in the usual manner, while the projections f are off from the enlarged part of the eyes, as seen in Fig. 3. Then when properly clasped the piece C is moved to bring the projections f over the enlarged part of the eye and in rear of the headed stud a of the other part of the clasp. Because of thus covering the enlarged part of the eye the studs cannot move in the eye so as to bring the head of the studs into a position to pass through the eye and be detached, hence are locked in their place until the wearer shall move the piece C into the position seen in Fig.

3, to open the enlarged part of the eye. In that condition the clasps are detached in the usual manner. The edge of the projections f are inclined on that side which passes onto the openings, the said inclines serving to force the studs into the narrower part of the eye. 55

To move the piece C, a loop, D, is attached to one end of the busk B, hinged to the busk by a cross-bar, h. To the upper bar, i, of the loop the piece C is attached, as shown. The lower part of the loop lies against the busk, as seen in Fig. 4, when in its normal condition—that is, the condition of closing the eyes. When it is desired to open the eyes for the insertion of the studs, turn the loop D up, as indicated in broken lines, Fig. 4, which draws the piece C downward, and as also seen in Fig. 3.

The piece C, being made from elastic metal, 70 serves as a spring to hold the loop in its normal condition. Turning the loop downward, as seen in broken lines, Fig. 4, throws the lower end of the piece C away from the piece B, thus applying the spring, the tendency of 75 which would be to throw the loop back again.

If the locking projections f present only a thin plate over the opening and beneath the head of the stud, there will be a liability by the twisting strain, which sometimes comes 80 upon the busks, for the head, striking upon the flat projection, to force its way through the opening—that is, pressing the projection away therefrom. To avoid this I turn up the outer end of one or more of the projections f, as at 85 m, Fig. 5, and make a corresponding slot, n, in the eye, as seen in Figs. 2 and 3, through which that projection will pass and stand in front of the stud, as seen in Fig. 5.

Instead of the longitudinal movement of the 90 piece C, it may be constructed with diagonal slots, as at r, Fig. 6, which will impart to the sliding piece C a combined longitudinal and transverse movement, and will carry the projections over or away from the enlarged part 95 of the openings in the eyes, as indicated in Fig. 6; or the covering-projections may be hinged to the busk B, as at s, Fig. 7, and also hinged to the sliding piece C, so that as the piece C is moved up and down it will turn onto 100 or off from the enlarged part of the eye, as indicated in Fig. 7; or they may be otherwise ar-

ranged, it only being essential that there shall be a locking-piece which may be moved over the eye so as to cover the enlarged part of the eye to lock the studs or remove therefrom to release them.

Instead of employing the sliding piece C as the spring to hold the loop D, other springs may be applied—as, for instance, the cap E, which lies over the bar h, may be elastic and the bar flat, as shown, so that when the loop is turned the flat bar will force the spring outward, and, returning, the spring will hold the loop in place. The loop for moving the slide may be either at the upper or lower end of the 15 clasp.

I do not broadly claim a device to lock the stud in the narrower part of the eye, as such; I am aware, is not new. Neither do I broadly claim a longitudinally-sliding piece on the eye 20 part of the corset, as such, I am aware, is not new.

I claim—

1. In a corset, the two busks A B, one provided with headed studs and the other with 25 eyes having an enlarged opening for the insertion of the heads, the combination therewith of a lock arranged upon the busk to which the eyes are attached, but independent of the eyes and studs, and so as to be moved over and 30 close the enlarged part of the opening in the eye to lock the clasp together, or removed therefrom to permit their separation, substantially as described.

2. In a corset, the two busks A B, one provided with headed studs and the other with 35 eyes having an enlarged opening for the insertion of the heads, the combination therewith of a lock arranged to slide over and close the enlarged part of the opening in the eye to lock 40 the clasp together, or removed therefrom to permit their separation, one or more of the said

eyes constructed with a slot, n, and the lock with a projection, m, working through said slot, substantially as and for the purpose described.

3. In a corset, the two busks A B, one provided with headed studs and the other with eyes having an enlarged opening for the insertion of the heads, the combination therewith of the piece C, arranged to slide upon that part to which the eyes are attached, the said piece C carrying a part or projection which by the sliding movement of the said piece C will carry such part or projection over or remove it from the enlarged part of the opening in the eye, 55 substantially as described.

4. In a corset, the two busks A B, one provided with headed studs and the other with eyes having an enlarged opening for the insertion of the heads, the combination therewith of the piece C, arranged to slide on the part to which the eyes are attached, with the loop D, hinged to the part B and to the piece C, whereby movement is imparted to the said piece C to cover or uncover the enlarged part of the 60 openings in the eyes, substantially as described.

5. In a corset, the two busks A B, one provided with headed studs and the other with eyes having an enlarged opening for the insertion of the heads, the combination therewith of the piece C, arranged for longitudinal movement on that part to which the eyes are attached, and carrying projections f to pass over or from the enlarged part of the openings in 70 the eyes, constructed with inclines upon their edge next the eye, substantially as described.

DENNIS H. TIERNEY.
